UNITED STATES PATENT OFFICE.

JAMES R. ROBINSON, OF MONONGAHELA, PENNSYLVANIA.

AUTOMATIC DUMPING APPARATUS.

SPECIFICATION forming part of Letters Patent No. 640,952, dated January 9, 1900.

Application filed July 6, 1899. Serial No. 722,956. (No model.)

To all whom it may concern:

Be it known that I, JAMES R. ROBINSON, a citizen of the United States, residing at Monongahela, in the county of Washington and State of Pennsylvania, have invented a new and useful Automatic Dumping Apparatus, of which the following is a specification.

My invention relates to improvements in an automatic dumping apparatus especially adapted for use in mine-shafts for unloading a car which may be hoisted through the shaft; but the principle of the invention may be availed of in other relations where it is desirable to automatically dump a car or receptacle for the purpose of unloading the contents thereof.

One of the leading features of my invention is the provision of a cage arranged to automatically tilt a car or its equivalent into a discharge-chute before the car is emptied of its contents, thus overcoming the tendency of the load to fall or spill down the mine-shaft.

A further object of the invention is to arrange the parts for service in a manner to utilize a part of the weight of the load and the car for moving the latter to its dumping position, thus minimizing the expenditure of the power required to unload the car.

With these ends in view the invention consists in the novel combination of elements and in the construction and arrangement of the parts for service, as will be hereinafter fully described and claimed.

To enable others to understand the invention, I have illustrated a preferred embodiment thereof in the accompanying drawings, forming a part of this specification, and in which—

Figure 1 is an elevation of my improved dumping-cage, representing the same in operative relation to the framing of a mine-shaft and carrying a car which is to be automatically dumped by engagement with an eccentric guide when the cage reaches the place of discharge. Fig. 2 is an elevation at right angles to Fig. 1 and showing the cage-frame guided slidably by parts of the framing of the mine-shaft. Fig. 3 is a vertical sectional elevation of the cage, representing the platform and the car thereon in their dumping positions for automatically unloading the car. Fig. 4 is a detail perspective view of my im-

proved dumping-cage removed from the framing of the mine-shaft.

The same numerals of reference are used to indicate like and corresponding parts in each of the several figures of the drawings.

The dumping-cage of my invention is indicated in its entirety by the numeral 10, reference being had more particularly to Fig. 4 of the drawings, said cage adapted to bodily carry a loaded car or its equivalent. This cage consists of a tilttable platform 11, the carrying-frame 12, a pair of short arms 13, and another pair of long arms 14, said pairs of arms adapted to pivotally connect the platform with the cage-frame for the purpose of imparting a swinging movement in an upward direction to the platform and the load thereon when the cage reaches the point where the load is to be discharged automatically.

The platform 11 is fastened to a pair of side bars 15 of angle-iron construction and arranged at opposite edges of the platform to lie parallel to each other, and this platform carries the track-rails 16, on which may rest the loaded mine-car, as shown by Fig. 1. The metallic side bars 15 of the tilttable platform support the cross shafts or rods 17, arranged transversely near the opposite ends of said platform, said shafts or rods having the upper ends of the arms 13 14 sleeved loosely thereon.

The frame 12 of the dumping-cage consists of the head-rail 18, a pair of bottom rails 19 20, and the upright connecting rods or braces 21 22. The bottom rails 19 20 are preferably of channeled bar metal and arranged parallel with each other below the tilttable platform. The head-rail 18 is preferably of metal, and it is arranged centrally with relation to the cage and at right angles to the bottom rails 19 20, so as to span the platform, while allowing ample space for the platform and its load to assume the inclined or dumping position. The connecting-rods 21 22 are arranged in pairs on opposite sides of the cage, each pair of rods having its members diverging from the head-rail 18 toward the ends of one bottom rail 19 or 20, said ends of the connecting-rods being fastened firmly to the rails of the cage-frame in any approved manner.

The bottom rails of the cage-frame support the cross-shafts 23, which are suitably mount-

ed in said rails, and these cross-shafts have the lower ends of the arms 13 14 sleeved loosely thereon. In this specification I have described that the cross-shafts 17 21 are mounted on the platform and the cage-frame, respectively, in fixed positions and that the links or arms 13 14 are sleeved at their respective ends on said shafts. As an equivalent for this construction it is evident that 5 the cross-rods may be mounted to rock or turn in bearings on the platform and cage-frame, respectively, and that the links or arms may be made fast with said shafts.

By reference to Figs. 1 and 3 of the drawings it will be noted that the arms 14 are considerably longer than the arms 13. The tilt- 15 able platform 11 is adapted to assume a horizontal position parallel with the bottom rails 19 of the cage-frame during the vertical travel 20 of the cage through the mine-shaft, and in this horizontal position of the platform the long links or arms 14 are adapted to assume the inclined positions shown by Figs. 1 and 4, while the short links or arms 13 occupy a 25 substantially vertical position. To sustain the end of the platform to which the long links are connected, I employ a rest-frame 26, which is fixed to the bottom rails 19 20 of the cage-platform to occupy a position at right 30 angles to said rails, said rest-frame being stayed in place by the inclined struts 27.

The cage of my invention is adapted to travel through the mine-shaft in a vertical direction, and to prevent this cage from swaying 35 I have provided the cage-frame 12 with guides adapted to slidably embrace suitable guide posts or ways of the framing in the mine-shaft. These guides may be of any suitable construction known to those skilled 40 in the art; but in the exemplification of the cage represented by the accompanying drawings the guides 24 24 are attached to the ends of the head-rail 18 and the guides 25 25 are fastened to the middle of the bottom rails 19 45 20, respectively. Each guide is preferably substantially U-shaped, so as to present the appearance of a clip, and the guide 24 on one side of the cage, at the top thereof, is in vertical alinement with the guide 25 on the same 50 side of the cage, at the lower end thereof.

That end of the platform to which the short links 13 are pivoted carries a roller 28, which extends from the side of the platform and is loosely journaled on an axle 29, that is fixed 55 to the platform in any suitable way. For the attachment of the elevating chain or cable I have shown the head-rail 18 of the cage-frame as equipped with a series of eyebolts 30. The elevating chain or cable 31 has a series of stay-chains 32 connected thereto, said stay-chains being attached to the eyebolts 60 on the head-rail of the cage-frame.

A part of the framing 33 ordinarily employed in a mine-shaft is represented by Figs. 65 1 to 3, inclusive, said framing having the guide posts or ways 34, which are embraced by the guides 24 25 of the cage-frame, whereby

the cage is caused to travel in a perpendicular path on its ascent or descent in a mine-shaft, and the cage is not only prevented from 70 swaying, but it is also restrained from tilting with the platform in unloading the car thereon by its engagement with the posts or ways 34.

The framing 33 in the mine-shaft carries 75 an eccentric guide 35, which is fixed to the framing, so as to lie in the path of the roller 28, and is situated at the place where it is desired to discharge the load from the cage. This eccentric guide is shown by Fig. 1 as 80 consisting of a pair of curved plates, which are bolted to the frame and arranged in such relation one to the other as to form an intermediate channel 36, which is open at its ends to form the throats 37. (See Fig. 1.) 85

An ordinary mining-car 38 of any suitable construction is shown as resting on the rails of the platform in Fig. 1 and in its dumping position in Fig. 3.

The operation is as follows: When the cage 90 is lowered to the bottom of the mine-shaft, the short arms 13 assume a vertical position, the long arms 14 are inclined, and the platform 11 is in a horizontal position, with one end resting on the short frame 26, while its 95 other end is supported by the vertical short arms 13. A loaded mine-car, as 38, is run from the tracks in the bottom of the mine onto the track of the horizontal tilttable platform 11, said car being locked or held against 100 movement on the platform by any suitable means. During the elevation of the cage the platform and car remain in their horizontal positions, while the cage is restrained against swaying by the engagement of the guide-clips 105 24 25 with the posts or ways 34. As the cage approaches the place of discharge the rollers 28 enter the throat 37 of the eccentric guide 35, and as the cage continues to ascend the eccentric guide draws the tilttable platform to 110 one side or gives an endwise movement thereto in the direction of the arrow shown by Fig. 3, thereby turning the links or arms on their pivotal connections with the platform and the cage-frame, respectively. By reason of 115 the difference in the lengths of the arms 13 14 and the engagement of the rollers on the platform with the eccentric guides the front 120 end of the platform is swung in a downward and forward direction, while the rear end of the platform is moved in an upward and forward direction, such upward movement being due to the long links 14 assuming the substantially vertical position shown by Fig. 3. This operation of the eccentric guide on 125 the platform and the dropping of the short links with the simultaneous elevation of the long links makes the platform 11 assume the tilted dumping position shown by Fig. 3, and the car 38 partakes of the tilting movement 130 of the platform, whereby the car is placed in the ordinary discharge-chute before any of its contents are dumped, and hence the load is not spilled in the mine-shaft. It is also to

be observed that the short links permit one end of the platform to drop, while the long links raise the other end of the platform in a manner to utilize some of the weight of the load and car for completing the movement of the platform to its dumping position, thus reducing the power required for operating the automatic dump. On the descent of the cage the eccentric guide and roller coact to restore the platform to its horizontal position, the frame 26 supporting the rear end of the platform, while the short links 13 sustain the front end thereof.

Changes may be made in the form and proportion of some of the parts while their essential features are retained and the spirit of the invention embodied. Hence I do not desire to be limited to the precise form of all the parts as shown, reserving the right to vary therefrom.

Having thus described the invention, what I claim is—

In an automatic dumping-hoist, the combination of a vertically-traveling cage having the bottom rails and the central head-rail

united together by intermediate rods and also provided on said head-rail and the bottom rails with the guides which, on each side of the cage, are vertically alined, a rest-frame secured to the bottom cage-rails and connect- 30
ed together by a cross-rail, a tilttable platform, shafts supported on the platform and the bottom rails of said cage, the short links sleeved on the shafts near one end of the cage and the platform, the long links sleeved on 35
the shaft near the other end of the platform and the middle of the cage, the rollers mounted on the platform near the points where the short links are pivoted thereto, the uprights or posts fitting in the cage-guides, and the 40
curved guides fixed in the path of the rollers on said cage, substantially as described.

In testimony that I claim the foregoing as my own I have hereto affixed my signature in the presence of two witnesses.

JAMES R. ROBINSON.
